CLAIM

The ornamental design for a table, as shown and described.

DESCRIPTION

This application is related to commonly assigned, co-filed U.S. design patent application Ser. No. 29/792,659, filed on Apr. 14, 2022, by Jeffrey Taly, entitled “Planter”; commonly assigned, co-filed U.S. design patent application Ser. No. 29/792,661, filed on Apr. 14, 2022, by Jeffrey Taly, entitled “Seat”; and commonly assigned, co-filed U.S. design patent application Ser. No. 29/792,662, filed on Apr. 14, 2022, by Jeffrey Taly, entitled “Furniture”; which applications are incorporated herein by reference in their entireties.

FIG. 1 is a front right perspective view of a table according to the new design;

FIG. 2 is a rear left perspective view thereof;

FIG. 3 is a front elevational view thereof;

FIG. 4 is a right side elevational view thereof;

FIG. 5 is a left side elevational view thereof;

FIG. 6 is a rear elevational view thereof;

FIG. 7 is a top view thereof;

FIG. 8 is a bottom view thereof; and,

FIG. 9 is a front right perspective view thereof.

The broken lines in the drawings illustrate portions of the table and form no part of the claimed design.

The long dash-dot-long dash lines in the drawings represent a boundary of the claimed design.

1 Claim, 9 Drawing Sheets
